[57] CLAIM

The ornamental design for a combined telephone and stand therefor, as shown and described.

DESCRIPTION

FIG. 1 is a front elevational view of a combined telephone and stand therefor showing my new design, and with portions of the cord broken away;

FIG. 2 is an elevational view of one side thereof with portions of the cord shown in phantom line;

FIG. 3 is a top plan view thereof;

FIG. 4 is a bottom view thereof;

FIG. 5 is a rear elevational view thereof;

FIG. 6 is an elevational view of the side opposite that shown in FIG. 2;

FIG. 7 is a front elevational view with the handset removed; and

FIG. 8 is a top plan view with the handset removed. As indicated by oblique angle surface shading, the case and stand for the telephone, (but not the handle) are transparent. The appearance and orientation of internal telephone components will vary, and these components are not shown since they are not a part of the design claimed.
